UNITED STATES PATENT OFFICE.

ISAAC Q. GURNEE, OF BUTLER, NEW JERSEY, ASSIGNOR TO THE AMERICAN HARD RUBBER COMPANY, OF NEW YORK.

DESIGN FOR AN ATOMIZER-CASING.

SPECIFICATION forming part of Design No. 33,126, dated August 28, 1900.

Application filed December 7, 1899. Serial No. 739,578. Term of patent 14 years.

To all whom it may concern:

Be it known that I, ISAAC Q. GURNEE, a citizen of the United States of America, residing at Butler, in the county of Morris and State of New Jersey, have invented and produced a new and original Design for Atomizer-Casings, of which the following is a specification, reference being had to the accompanying drawings, forming part thereof.

10 My design consists in an atomizer-casing circular in form, having a circular rib upon each side near the circumference and a circular convex portion inward of each rib.

15 The accompanying drawings illustrate the design, Figure 1 being a perspective view of an atomizer embodying the design, and Fig. 2 being an edge view.

Similar letters of reference designate corresponding parts in both figures.

20 A designates the casing of an atomizer,

and B its nozzle. The casing is circular in form, and upon each side near the circumference it has a single annular laterally-projecting rib a, which constitutes a leading or essential feature of my design. Inward of 25 each of these ribs there is a circular convex portion b. The circumference is shown as being ornamented by astriated circumferential rib c.

What I claim, and desire to secure by Letters Patent, is—

The design for an atomizer-casing, substantially as shown and described.

In testimony whereof I have signed my name to this specification in the presence of 35 two subscribing witnesses.

ISAAC Q. GURNEE.
